UNITED STATES PATENT OFFICE.

ELIJAH F. SPAULDING, OF BROOKLYN, NEW YORK, ASSIGNOR TO ARTHUR ZIMTBAUM,
OF BROOKLYN, NEW YORK.

VENDING-MACHINE.

1,380,685.

Specification of Letters Patent.

Patented June 7, 1921.

Application filed December 9, 1919. Serial No. 343,506.

To all whom it may concern:

Be it known that I, ELIJAH F. SPAULDING, a citizen of the United States, and resident of New York city, borough of Brooklyn, in 5 the county of Kings and State of New York, have invented certain new and useful Improvements in Vending-Machines, of which the following is a specification.

My invention relates to improvements in 10 the class of vending machines wherein coins inserted in the machines are operated to discharge articles to be vended.

In my application for Letters Patent filed Dec. 14, 1918, Serial No. 266,719, for 15 improvements in vending machines, I have disclosed certain features of construction providing simple means for operating coins to discharge articles from the machine, as well as means to prevent washers from dis- 20 charging such articles, to prevent the accumulation of coins in the machine, and to prevent spurious tokens from being used to discharge articles. My present invention has reference to improvements in the class 25 of vending machines referred to and with reference to improvements in certain features disclosed in my aforesaid application.

My invention further comprises novel details of improvement and combinations of 30 parts that will be more fully hereinafter set forth and then pointed out in the claims.

Reference is had to the accompanying drawings forming part hereof wherein—

Figure 1 is a front view of a portion of a 35 vending machine embodying my invention;

Fig. 1^a is a detail section on line 1^a, 1^a, in Fig. 2;

Fig. 2 is a vertical section of Fig. 1 substantially on the line 2—2 in Fig. 1;

Fig. 3 is an enlarged detail section of 40 parts shown in Fig. 2;

Fig. 4 is a detail section on the line 4—4 in Fig. 5;

Fig. 5 is a front view of a portion of the 45 operating mechanism detached from the casing, parts being omitted;

Fig. 6 is a detail plan view of a coin receiver;

Fig. 7 is a side view thereof;

Fig. 8 is a cross section of Fig. 6;

Fig. 9 is a detail of the coin stop or gage;

Fig. 10 is a view somewhat similar to Fig. 6, illustrating the coin stop or gage in coin releasing position;

Fig. 11 is a detail side view of part of 55 the magazine and parts thereon;

Fig. 12 is a view looking from the right hand side of Fig. 11;

Fig. 13 is a detail plan view of part of 60 Fig. 12;

Figs. 14 and 15 are sectional details illustrating different positions of the parts;

Fig. 16 is an enlarged sectional detail 65 illustrating a coin slot and magnet adjacent thereto;

Fig. 17 is a face view looking from the left hand side in Fig. 16;

Fig. 18 is an edge view of the magnet.

Similar numerals of reference indicate 70 corresponding parts in the several views.

In the accompanying drawings the numeral 1 indicates a casing which may be of any usual or suitable construction, and is shown provided with a lower door portion 2 pivotally supported upon the casing at a 75 to swing outwardly, and an upper door portion 2^a which may be locked in the casing in any suitable or well known manner. A coin receptacle 3 is attached to door 2 and has an upper open end to receive coins after articles 80 have been discharged by the coins. Between said coin receptacle and door 2 is a passage or channel 4 open at the upper and lower ends and communicating with lower outlet 5 for discharge of unused coins, washers or 85 other tokens. A wall 6 provides a channel 7 between the casing and receptacle 3 for discharge of the articles 8 through opening 5. At 9 is a magazine or chute of any usual construction to receive stacks of articles 8 90 which may be supported in the casing over the receptacle 3 in any desired manner. Said magazine is shown provided with extensions 9^a supported upon way or plate 10 secured to the side walls of the casing. A 95 weight 11 rests upon articles 8 in the magazine or chute in ordinary manner. The lowermost article of the stack in the magazine rests upon spaced ledges 12 at the bottom of the magazine, the rear portion of the magazine being open at 13 to permit exit of the articles which are adapted to slide over de-

60

65

70

75

100

pending plate or guide 14 to drop into the channel 7. Between the magazine and receptacle 3 is a coin receiver 15 secured to rod 16 shown guided in a hole in plate 17 on 5 wall 2 in register with recess or hole 18 therein, whereby said rod can be pushed to move the coin receiver inwardly. The rod 16 is guided in a bearing in projection 19 from way or plate 10 and the inner end of 10 said rod is attached by a spring 20 to a depending lug 21 on said plate, whereby the receiver 15 is normally drawn toward the front of the machine. The receiver 15 is provided with a vertical opening or slot 15^a 15 to receive coins 22 from coin slot 23. Said slot is in plate 23^a shown secured to door 2 by screws 23^b (Fig. 17), the upper part of which plate is behind the lower part of door member 2^a, whereby the lower door is retained closed when the upper door is locked. 20 The plate 23^a is adapted to bear against stops A secured to the side walls of the casing to limit inward movement of door 2. The stops A are secured to the side walls of 25 the casing by screws a. Receiver 15 may have one or more openings or slots 15^a leading through it corresponding to the compartments for articles in magazine or chute 9. I have shown the magazine having two 30 compartments and the receiver having two openings 15^a corresponding to two coin slots 23. The upper receiving edges of the openings 15^a may be inwardly tapering as indicated in dotted lines, Fig. 7, to guide the coins into the openings. Said openings are 35 slightly wider than the coin. At 24 is a coin stop and gage slidably carried by the receiver, having its edge 24^a operable in corresponding opening 15^a of the receiver to 40 engage a coin in such opening to retain the coin suspended between said edge 24^a and the opposite edge 15^b of opening 15^a. (Figs. 45 6 and 7.) The stop and gage 24 is recessed at its edges at 24^c, (Figs. 6 and 9), and said stop is slidable in a slot in receiver 15 so that its edges 24^a may engage coins in openings 15^a when the stop is in one position, (Fig. 6), and when the stop is shifted to another position the recess 24^c will oppose 50 the coin or coins and release the same to fall below from the receiver. The stop 24 is shown provided with a head portion 24^d to retain the stop in its guide slot of the receiver. Said head is adapted to engage the 55 upright 19 as an abutment when the receiver is pushed inwardly to cause stop 24 to present its recesses 24^c in register with openings 15^a of the receiver to release the coin. The opposite end of the stop 24 is adapted to 60 engage an abutment 32 when the receiver approaches the normal coin-receiving position to cause stop 24 to be shifted to present its edges 24^a in the openings 15^a of the receiver to catch and retain coins. When stop 65 24 is in such position it will test the coins

and tokens in conjunction with the opposing edges 15^b of the opening 15^a so as to catch and retain the coins of proper diameter in the receiver and permit other coins or tokens to pass through opening 15^a.

70

When a proper coin is in the receiver the upper edge of the coin will slide close to and between spaced ledges 12 of the magazine, (Fig. 7). At 25 is a light spring secured to and extending over way or plate 10 in position for the lower edge of the coin to ride over the spring, the receiver being reduced at 15^c to pass over the spring. There will be one such spring for each coin opening 15^a. The ledges 12 retain the coin in proper position to pass over spring 25 when the receiver is pushed inwardly, the ledges resisting rise of the coin whereby when the coin passes said spring the latter will rise or snap up behind the coin to prevent return of the receiver with the coin in it, (Fig. 3). The construction of the machine is such as to prevent a coin having a string 26 attached to it that may have entered the receiver from being pulled back out of the receiver, (Fig. 3).

130

To guide the coins from coin slot 23 to corresponding opening 15^a of the receiver 15 I provide a plate 27 over the coin receiving location of the receiver and spaced from the front of magazine or chute 9, which plate is hung pivotally from its upper edge by means of lugs 27^a from said plate carried by brackets 28 secured on the magazine. (Figs. 3, 5 and 12.) One or more stops 29 at the lower end of plate 27 (Figs. 3 and 4), are adapted to engage the magazine to keep plate 27 spaced from the magazine when the receiver is in coin receiving position providing passageway b to guide the coins to openings 15^a of the receiver. (Figs. 2, 4 and 15.) An arm or lever 30 is pivotally supported at 31 upon abutment support 32 shown carried by way or plate 10, the rod 16 passing through abutment 32, the upper end of which arm or lever is operatively connected with plate 27 to swing the latter toward and from the magazine. The upper end of said arm or lever 30 is shown received in a recessed or loop-like member 33 secured to the outside of plate 27 within which the end of said arm is adapted to move freely, whereby when the arm is in one position it will push plate 27 toward magazine 9, providing passage b therebetween for the coins, and when said arm is in another position it will engage said member 33 and swing plate 27 outwardly and retain it temporarily in such position to release the coins or tokens that may be in passage b, (Fig. 3). The lower end 30^a of arm or lever 30 is adapted to rest upon rod 16 when the latter is pushed in and to enter a recess 16^a in said rod when the latter and the receiver are in normal position to cause arm 30 to retain member 27 to-

- ward the magazine, (Fig. 4). When the parts are in the last named position the coin 22 from slot 23 will slide through passage *b* and enter opening 15^a of the receiver, the 5 end 30^a of the arm 30 then being retained in recess 16^a of rod 16, (Fig. 4). When rod 16 and the receiver are pushed inwardly the end 30^a of arm or lever 30 will be pushed out of the recess 16^a, the rod 16 causing said arm 10 to tilt to swing plate 27 away from the magazine, and the lower end 30^a of arm 30 will ride upon rod 16 to retain plate 27 in the last named position until the receiver is returned to coin receiving position. The stop 15 24 at its end opposite arm member 30^a is forked at 24^e (Figs. 6 and 9), to receive the latter when the receiver returns to coin receiving position so that said stop can engage the abutment 32.
- 20 Upon the outer side of plate 27 is pivotally supported a rocking member 34 beneath the corresponding coin slot, which member is provided with projections 34^a and 34^b, one above the other, and which may be 25 spaced more than the diameter of a proper coin. Members 34 are pivotally supported at 35 upon plate 27 below the corresponding coin slot. The projections 34^a, 34^b operate in openings 27^b, 27^c of plate 27, (Fig. 5).
- 30 When a coin is in opening 15^a of the receiver such coin will engage corresponding projection 34^a and tilt member 34 so that its projection 34^b will be over passage *b* to prevent entrance of a coin or token (Fig. 15), 35 and the latter will, by the projection 34^b, be caused to fall away to one side without entering the receiver and will drop into space 4 to be returned through outlet 5 to the operator. When the coin moves away with the 40 receiver from projection 34^a the member 34 will tilt to carry projection 34^b outwardly to admit a coin to passage *b* and will so remain until another coin enters the receiver, (Fig. 14). I also provide washer catchers 36 pivotally supported upon plate 27 as at 37, 45 (Figs. 11 and 12) having lower projections 36^a operative through holes 36^b in plate 27, to enter holes in washers to prevent them from entering the coin receivers. When 50 plate 27 is moved outwardly the washers will fall below through channel 4 to be returned through opening 5. The members 34 and 36 are substantially the same as set forth in my aforesaid application Serial No. 55 266,719.
- At 37 is a magnet having a central portion 37^a extending lengthwise of and below coin slots 23 and shown located in a recess 38 in door 2 opposing a recess in plate 23^a, (Fig. 16), the spaced members 37^b of which magnet extend at an angle from the part 37^a forwardly over the adjacent portion of plate 23^a and are curved sidewise in the direction of coin receiver 15. Between the end members 37^b of the magnet is a guide 39 secured upon plate 23^a (Fig. 17). The outer portions of members 37^b are shown tapering outwardly. Coins and tokens inserted in the coin slot 23 pass between the guide 39 and the corresponding spaced member 37^b 70 of the magnet to drop into the passage *b* to be guided toward the receiver. In case magnetizable tokens pass through the coin slot they will be attracted by the member 37^b of the magnet to swing them to one side and prevent them from entering the receiver. 75
- The weight 11 has a projection 11^a extending through and in front of the corresponding channel of magazine 9 so that when the last article 8 to be delivered has 80 been discharged said projection will oppose a coin sliding from plate 23^a to deflect the coin and prevent it from passing through passage *b*, as indicated in dotted lines in Fig. 2.
- When rod 16 is pushed inwardly with a coin in the receiver the coin will discharge the lowermost article 8, and the coin will pass over the spring 25. When the receiver reaches a position near the termination of 90 its stroke the adjacent end of stop 24 will encounter abutment 19 and continued movement of the receiver will cause the coin to slide along said stop until the corresponding recess 24^c of the stop opposes the edge of 95 the coin, whereby the latter will be released to drop through opening 10^a of way or plate 10 into receptacle 3. When the coin receiver is pushed inwardly the recess 16^a of rod 16 will pass from arm member 30^a which will 100 ride upon said rod and cause arm 30 to be tilted to swing plate 27 away from the magazine to widen the passage *b*, whereby excess coins or tokens that may be on projections 29 as well as coins or tokens inserted in the 105 coin slot or slots while the receiver is advanced, will be deflected and fall below into channel 4 to return through outlet 5. If a washer should be hung upon the washer catcher 36 the washer will be dislodged and 110 fall into the channel 4. Light weight coins and tokens will be deflected from the receiver by projection 29 to fall into channel 4. Upon the return of the receiver to coin receiving position the stop 24 will engage 115 abutment 32 and continued travel of the coin receiver will cause the edges 24^a of the stop to be returned to position opposing the openings 15^a to receive coins. When the receiver about reaches the termination of its 120 return stroke the arm member 30^a will enter the recess 16^a of rod 16 and cause arm 30 to tilt to swing the plate 27 toward the magazine to retain the plate in such position positively until the rod and receiver are again 125 pushed inwardly.
- My improvements are simple in construction, cheap to manufacture, effective in use and not liable to get out of order.
- Changes may be made in the details of 130

construction set forth within the scope of the appended claims without departing from the spirit of my invention.

Having thus described my invention, what I claim and desire to secure by Letters Patent is:—

1. A vending machine comprising a magazine for articles, a coin receiver below the magazine having spaced openings for coins, a stop for coins slidably carried by said receiver between said openings, said stop having opposite edges to coincide with said openings when the stop is in one position to retain coins in the openings, said stop having notches on opposite sides to coincide with said openings when the stop is in another position to release the coins, and means to cause said stop to be shifted to coin retaining and releasing position. 10
2. A vending machine comprising a magazine for articles, a coin receiver below the magazine having spaced openings for coins, a stop for coins slidably carried by said receiver between said openings, said stop having opposite edges to coincide with said openings when the stop is in one position to retain coins in the openings, said stop having notches on opposite sides to coincide with said openings when the stop is in another position to release the coins, and spaced abutments on opposite sides of the receiver to engage said stop to shift it respectively to coin receiving and releasing positions. 20
3. A vending machine comprising a magazine having spaced ledges at its lower end for articles, a receiver operable below the magazine and said ledges and having an opening for coins, means to retain coins in and release them from the opening, a way below the receiver over which coins in the latter may pass, said ledges being in position to resist the rise of a coin in the receiver, and a spring over the way in position to permit the coin to pass thereover with the receiver and to prevent return of the receiver with the coin therein. 30
4. A vending machine comprising a magazine for articles and having a coin slot, a plate movably carried adjacent to the magazine below the coin slot, a coin receiver, a rod connected with the coin receiver below said magazine and plate, an arm operatively connected with the plate to move the latter toward and from the magazine to reduce and widen the space therebetween, said arm being controlled by said rod to shift and retain the plate, and means upon the plate to deflect excess coins when a coin is in the receiver in coin receiving position. 40
5. A vending machine comprising a magazine for articles and having a coin slot, a plate movably carried adjacent to the magazine below the coin slot, a coin receiver, a rod connected with the coin receiver below 50

said magazine and plate, an arm operatively connected with the plate to move the latter toward and from the magazine to reduce and widen the space therebetween, said arm being controlled by said rod to shift and retain the plate, a member movably carried by the plate and having upper and lower projections, the lower projection being in position to engage a coin in the receiver when the latter is in coin receiving position to retain the upper projection in the path of coins to the receiver to deflect them therefrom. 70

6. A vending machine comprising a magazine for articles and having a coin slot, a plate movably carried adjacent to the magazine below the coin slot, a coin receiver, a rod connected with the coin receiver below said magazine and plate, an arm operatively connected with the plate to move the latter toward and from the magazine to reduce and widen the space therebetween, said arm being operative by the rod to move and retain the plate away from the magazine when the receiver is out of coin receiving position, said rod having a recess to coöperate with said arm for movement of the plate toward the magazine and to retain it there when the receiver is in coin receiving position, and means upon said plate to prevent entrance of light weight coins and tokens into the receiver as well as excess coins and tokens when the plate is held toward the magazine. 80

7. A vending machine comprising a magazine for articles and having a coin slot, a plate pivotally supported at one side of the magazine providing a passage therebetween for coins, a coin receiver below the magazine and plate, a rod connected with the receiver to operate it and provided with a recess, an arm pivotally supported and having a member to coöperate with the rod and its recess, and a recessed member upon the plate receiving the upper end of the arm for moving the plate outwardly, said arm being coöperative with the plate to move it toward the magazine, the recess of the rod being in position to receive said arm to retain the plate toward the magazine when the receiver is in coin receiving position, and means upon the plate to prevent the admission of excess coins and tokens to the receiver. 100

8. A vending machine comprising a magazine for articles and having a coin slot, a receiver for coins below the magazine, means operatively supporting the receiver, and a spring below the receiver over which coins may ride, the spring being adapted to rise behind a coin in the receiver to prevent return of the receiver, said magazine having spaced ledges over the receiver in position to be engaged by the upper portion of a coin in the receiver to limit rising of the coin when it passes over said spring. 110

9. A vending machine comprising a casing having a coin slot, a magnet having a portion 130

extending lengthwise of and below the coin slot and received in a recess in the casing, said magnet having a portion extending forwardly along which the coin slides, and a 5 guide spaced from said forwardly extending portion of the magnet providing a passage therebetween for coins and tokens from the coin slot.

10. A vending machine comprising a casing having a coin slot, a magnet having a portion extending lengthwise of and below the coin slot and received in a recess in the casing, said magnet having a portion extending forwardly, as a guide for coins and tokens and a guide spaced from said forwardly extending portion of the magnet providing a passage therebetween for coins and tokens from the coin slot, the outer part of

said portion being curved sidewise to deflect magnetizable tokens. 20

11. A vending machine comprising a casing having spaced coin slots, a magnet having a portion extending lengthwise of and below the coin slots and received in a recess in the casing, said magnet having spaced 25 portions extending forwardly as a guide for coins and tokens, and a guide between said forwardly extending portions of the magnet providing passages between the guide and said portions for coins and tokens from the 30 coin slots respectively.

Signed at New York in the county of New York and State of New York this 4th day of December, A. D. 1919.

ELIJAH F. SPAULDING.
